LEWIS ERNEST HOPKINS, OF CARDIFF, WALES.

HYDRAULIC TRANSMISSION.

1,091,137.

Specification of Letters Patent. Patented Mar. 24, 1914.

Application filed May 27, 1913. Serial No. 770,155.

To all whom it may concern:

Be it known that I, LEWIS ERNEST HOPKINS, subject of the King of Great Britain, residing at 189 City road, Cardiff, in the county of Glamorgan, Wales, have invented new and useful Improvements in Hydraulic Transmission, of which the following is a specification.

This invention relates to improvements in rotary pumps and hydraulic motors of the type in which the volume of liquid delivered or supplied respectively per revolution can be varied as desired. Further the hydraulic machine, which can be employed 10 as a pump or a motor, is of the type in which a rotor secured to a shaft is formed with a plurality of radially situated cylinders equi-angularly situated relatively to each other, each cylinder being fitted with a 15 piston. These pistons are so connected to the stator that in the revolution of the rotor they are constrained to move in a path which is approximately a circle, whose center is eccentric to the axis of revolution of 20 the rotor whereby with each revolution of the rotor each piston performs a double stroke within its cylinder. Moreover the liquid flows into and out of the cylinders from and into, respectively, an annular 25 space provided between the outer boundary of the rotor and the inner surface of the stator casing.

Now according to the present invention the liquid is supplied to and delivered from 30 the said annular space by a pair of passages which are situated approximately at the opposite ends of a diameter which contains the center of the eccentric circular orbit of the pistons, and the annular space is divided 35 into two portions by a pair of partitions situated approximately diametrically opposite each other, the said partitions being carried by a disk so mounted that the said partitions are adapted to be angularly displaced within the annular space relatively 40 to the stator, means being provided whereby the partitions can be set to occupy any desired angular position relatively to the line joining the admission and eduction passages 45 for the liquid.

The length of each partition, as measured in the direction of the circumference

of the annular passage, is made approximately equal to the diameter of the cylinders in order to avoid any cylinder from 55 being in communication with the annular space on both sides of a partition for more than a relatively small portion of time. With this arrangement it will be observed that, if the partitions are placed with the 60 line which joins their centers at right angles to the line through the admission and eduction passages and the rotor is rotated, then from and to each half of the annular space just as much liquid will be drawn into 65 the cylinders as will be evacuated therefrom and therefore no liquid will flow from the admission to the eduction passage. If from this position the partitions are angularly displaced, more liquid will be drawn into 70 the cylinders from one half of the annular space than will be evacuated into that half space from the cylinders, whereas from the other half space less liquid will be drawn into the cylinders than will be evacuated 75 therefrom. Accordingly, liquid will enter the annular space on one side of the two partitions from one of the passages and an equal quantity of liquid will be delivered through the other passage from the portion 80 of the annular space on the other side of the partitions.

Supposing the rotor to revolve in either direction and the partitions to be angularly displaced in the same direction, then liquid 85 will be admitted through the passage which is nearer the center of the eccentric orbit of the pistons and will be delivered through the other passage. If, on the other hand, the partitions are angularly displaced in a 90 direction opposite to that of the rotation of the rotor the direction of the flow of liquid will be reversed.

When the partitions are angularly situated so as to be as nearly in the line of the 95 admission and eduction passages as possible, without obstructing the flow through those passages, then the quantity of liquid transferred from one passage to the other, per revolution of the rotor, will be equal to 100 the volume of displacement of all the pistons carried by the rotor. When the partitions are situated in an intermediate position the quantity of liquid transferred

from one passage to the other will be a fraction of the total displacement volume, the magnitude of which will depend on the angle through which the partitions have been shifted from a line at right-angles to the line of the two passages. If, instead of the rotor being driven by mechanical energy applied to the shaft to which it is secured, in which case the machine will operate as a pump, high-pressure liquid is supplied through one of the passages and the other passage is in communication with a space of low pressure, the liquid in forcing its way from the first to the second-mentioned passage will rotate the rotor against a resistance, and the machine will operate as a motor. With a given difference of pressure the torque exerted will depend on the angular situation of the partitions and the expenditure of liquid will correspondingly vary, enabling the power of the motor to be varied, within wide limits, without altering the pressure of the urging liquid or the speed of revolution of the rotor.

When the rotor is urged by high-pressure fluid, as above described, the direction in which it will rotate can be reversed by altering the direction of the angular shift of the partitions. If, for example, the high-pressure liquid is supplied through the passage nearer to the center of the eccentric orbit of the piston, the rotor will revolve in a clock-wise direction if the partitions are shifted clockwise and, alternatively, the rotor will revolve anti-clockwise if the partitions are shifted anti-clockwise.

The possession of the double property of being adapted to perform the function of a motor or a pump, as desired, renders the machine peculiarly efficient as a hoisting engine which is required not only to raise but also to lower weights.

Suppose, for the purpose of raising a weight, the machine is supplied with high-pressure water which water is delivered into a low-pressure tank and subsequently the same weight is required to be lowered:— To permit the weight to be lowered the partitions must be shifted somewhat toward the neutral position from that which they occupied when hoisting, the weight will then be allowed to run down and in so doing will reverse the direction of rotation of the rotor and cause it to operate as a pump and transfer a portion of the water from the low-pressure tank to the high-pressure source and so store up some energy for the next hoisting operation. In this manner the controlling effect of a brake will be derived, but instead of the energy of descent being wasted in friction it will be partially conserved for future use.

Besides being used as a pump or a motor or both combined, as just described, one or 65 a couple of such hydraulic machines may

be employed as a variable speed, and reversing, transmission-organ in which liquid forced by one of the machines by the application of mechanical energy to the shaft of its rotor is delivered to the other machine 70 and the shaft of its rotor urged to rotate against a resistance, the liquid being returned from the second machine to the first in a closed continuous circuit.

If the partitions of the two machines are 75 so set that the volume of liquid transferred from the admission to the eduction passage in one machine during a revolution differs from that transferred in the other machine during a revolution thereof, then the speed 80 of revolution of the one rotor must be so much greater or less than that of the other in the inverse ratio to that of the ratio of volumes transferred. By varying the transferred volume of liquid of one machine or 85 of both machines oppositely or differentially, power can be transmitted with a velocity ratio capable of being varied in a gradual manner and within very wide limits. Such a combination interposed between the engines and the driving wheels of 90 a motor car could be substituted for the change-speed gear hitherto in use, and provide an unlimited range of speed-ratio values.

Any appropriate known device for constraining the orbital motion of the pistons may be adopted, and preferably that in which each piston is united by a connecting-rod to a pin secured to the stator, the 100 one pin serving in common for all the pistons. Also any suitable means may be employed for shifting the angular position of the partitions as, for example, spur-wheels, spur-wheel and rack or sector, or worm-and-worm-wheel. By the use of the latter the partitions will be retained where set without other means for locking.

Packing rings and strips are employed to insure stanch joints in a manner employed for like purposes in other fluid-pressure machines.

The above described invention is illustrated on the accompanying drawings by an application thereof as a variable speed-ratio and reversing rotary power-transmitter such as may, for example, be substituted in motor-cars for the multiple, spur-wheel, speed-gears hitherto in use.

In these drawings:—Figure 1 is a longitudinal section of the mechanism, and Fig. 2 is a part end elevation of the stator with the cover and rotor removed. Fig. 3 is a transverse section taken along the line 3—3 of Fig. 1, and Fig. 4 is the central portion 125 of the plan view of the mechanism.

In these figures, *a* is the driving shaft which connects the car-engine with the rotor *A* of the pump, and *b* is the driven shaft which connects the rotor *B* of the hydraulic- 130

motor with the Cardan shaft by which the power is transmitted to the driving-wheels of the car. According to this construction the rotors of both the pump and the hydraulic-motor are contained within the same casing C, and the liquid delivered by the pump finds its way by a passage within the casing to the motor and returns to the pump through another similar passage.

10 In each rotor A and B are provided eight radially-bored cylinders, each fitted with pistons. Seven pistons $d \dots d$ of the pump are, by connecting-rods $e \dots e$, attached to a strap e^0 which embraces a pin F which is secured to the stator, the said strap and the rod-extension thereof serving to connect the eighth piston d^0 to the pin F. By such means, on each revolution of the rotor the pistons will perform a double-stroke within their respective cylinders, the length of the stroke being twice the radial distance between the axis of rotation of the rotor and the axis of the pin F.

15 It will be observed that the construction is such that the same pin F serves to determine the orbital path of the pistons g of the hydraulic motor-rotor B as well as those of the pump-rotor A.

20 The pump-rotor A is connected to the driving shaft a by means of a flange a^1 formed integrally with the shaft. The shaft and the rotor are mounted to rotate freely on a set of ball-bearings a^3 on the one side and another set of ball-bearings a^4 on the other side. The motor-rotor B is correspondingly secured by the flange b^1 to the driven shaft b and likewise mounted on two sets of ball-bearings b^3 and b^4 .

25 The entire space within the case C is occupied by liquid of a lubricating character, such as oil for example, apertures fitted with screw-plugs being provided for the purpose of admitting the liquid and permitting the evacuation of the air.

30 Around each rotor an annular space c is provided, the spaces c being interconnected by a passage c^1 , formed within the upper side of the casing, and a corresponding passage c^2 formed within the underside of the casing. In the annular space c of the pump are fitted two partitions $h h$ which project inwardly from the face of a disk H which is interposed between the pump-rotor A and the cover c^0 of the casing and so mounted as to be angularly-displaceable about the axis of the rotor.

35 According to Fig. 1 the angular displacement of the disk H and its partitions, which latter are located approximately diametrically opposite each other, are adapted to be effected through the medium of a spur-wheel h^1 which is secured around the boss of the disk H and a pinion k which is secured to a partition-adjusting spindle K which

emerges fluid-tight from the casing C 65 through a stuffing-box c^3 .

Supposing the partitions $h h$ are set in positions such that their center line is at right-angles to the center line through the ports leading to the before-mentioned passages 70 $c^1 c^2$ then, whichever way the rotor is rotated, just as much liquid will be evacuated by the pistons into the annular space c on one side of the partitions as will be drawn from that space by the pistons into the revolving cylinders. Accordingly in such a position of the partitions the pump will be inoperative. If from this position the partitions are angularly displaced in the same direction as that of the rotation of the rotor, liquid will be drawn through the port nearer to the pin F and evacuated from the port opposite thereto. If, on the contrary, the partitions are angularly displaced in a direction opposite to that of rotation of the 80 rotor, the direction of flow of the liquid through the pump will be reversed. The more the partitions are displaced from the neutral positions, the greater will be the quantity of liquid circulated by the pump, 85 per revolution of the rotor.

90 As exhibited in the drawing, the partitions which divide the annular space of the motor-stator into two compartments are not angularly displaceable but are permanently 95 located at c^4 , the extremity of the diameter which passes through the axis of the pin F (Fig. 2) and are therefore so set as to admit to and deliver from the stator, per revolution of the rotor, the maximum quantity of 100 liquid.

95 The rotor B of the motor being identical with that of the rotor A of the pump, both rotors will run at practically the same speed when the partitions $h h$ of the pump are set 105 to circulate the maximum quantity of liquid. By angularly displacing the partitions toward the neutral position the velocity-ratio of motor to pump will be gradually diminished and, inasmuch as the virtual-leverage 110 of the liquid resistance to the rotation of the pump-rotor will thereby be correspondingly diminished, and, assuming the torque transmitted by the engines to the pump-rotor to be unaltered, the liquid pressure set up in 115 the casing and transmitted to the pistons of the motor will be correspondingly augmented with equivalent increase of the torque exerted on the driven-shaft b.

120 If instead of angularly displacing the partitions $h h$ from the neutral position in the direction of rotation of the rotor they are displaced in a contrary direction, the flow of liquid through the pump will be reversed in direction and consequently the direction 125 of rotation of the rotor B of the motor will be reversed.

125 As shown, the design is only a speed-re-

ducing and reversing gear, but if the partitions c^1 of the motor were also made angularly displaceable, the function of the mechanism would be extended to serve also as a speed-increasing gear. In addition to operating as a speed-reducing and reversing-gear, the above described construction can very effectively serve the purpose of a brake.

Suppose the car to be descending an incline under the influence of gravity and it is requisite to absorb a portion of the energy which is being developed in order to avoid undue speed, then, under such circumstances, what was the motor becomes a pump and the liquid circulated thereby is adapted to serve as an absorber of the superfluous energy without incurring any detrimental effect on the mechanism. When what is normally the motor operates as a pump, the circulation of the liquid through the pump proper will be in the contrary direction to that which occurs when the pump proper is urging the machine in the forward direction.

The superfluous energy may be taken up by causing the liquid circulated by what constitutes normally the motor to undergo very rapidly repeated admission to and evacuation from the cylinders of what is normally the pump, by displacing the partitions h toward their neutral positions. Alternately the partitions may be so shifted as to constrict the flow through the ports leading from and to the before-mentioned passages c^1 c^2 and the superfluous energy be dissipated by the abrupt changes of velocity and consequent eddying-motion to which the liquid will be subjected.

I claim:

1. A rotary machine comprising a rotor formed with a plurality of radially-directed cylinders fitted with pistons, means for connecting said pistons to the stator such that they pursue an orbital path eccentric to the axis of the rotor, an inclosing stator which provides an annular space around said rotor, a passage leading to said annular space and one leading therefrom, partitions dividing said annular space into a plurality of compartments, and means for displacing said partitions angularly relatively to the stator.

2. A rotary machine comprising a rotor formed with a plurality of radially-directed cylinders fitted with pistons, means for connecting said pistons to the stator such that they pursue an orbital path eccentric to the axis of the rotor, an inclosing stator which provides an annular space around said rotor, a passage leading to said annular space and one leading therefrom the ports of which are situated approximately at the extremities of a diameter of the stator which contains the center of the orbit of the pistons, partitions situated

approximately diametrically opposite each other and carried by a disk and means for angularly displacing said disk and the partitions carried thereby.

3. A rotary machine comprising a rotor formed with a plurality of radially-directed cylinders fitted with pistons, a pin secured to the stator with its axis parallel to that of the rotor at a distance therefrom equal to half the stroke of the pistons, a strap embracing said pin, rods connecting said strap to all but one of said pistons by a pin-connection, the rod of the latter being formed integrally with the strap, an inclosing stator which provides an annular space around said rotor, a passage leading to said annular space and one leading therefrom the ports of which are situated approximately at the extremities of a diameter of the stator which contains the center of the orbit of the pistons, partitions situated approximately diametrically opposite each other and carried by a disk and means for angularly displacing said disk and the partitions carried thereby.

4. A power-transmitter of variable speed-ratio, comprising a combination of a rotary pump and a rotary motor in which the pump and also the motor comprise a rotor formed with a plurality of radially-directed cylinders fitted with pistons, means for connecting said pistons to the stator such that they pursue an orbital path eccentric to the axis of the rotor, an inclosing stator which provides an annular space around said rotor, a passage leading to said annular space and one leading therefrom the ports of which are situated approximately at the extremities of a diameter of the stator which contains the center of the orbit of the pistons, partitions situated approximately diametrically opposite each other and carried by a disk and in one element of the pump-motor combination means for angularly displacing said disk and the partitions carried thereby.

5. A power-transmitter of variable speed-ratio, comprising a combination of a rotary pump and a rotary motor in which the pump and also the motor comprise a rotor formed with a plurality of radially-directed cylinders fitted with pistons, a pin secured to the stator with its axis parallel to that of the rotor at a distance therefrom equal to half the stroke of the pistons, said pin of pump being formed integrally with said pin of motor, a strap embracing said pin, rods connecting said strap to all but one of said pistons by a pin connection the rod of the latter being formed integrally with the strap, an inclosing stator which provides an annular space around said rotor, a passage leading to said annular space and one leading therefrom the ports of which are situated approximately at the extremities of a diameter of the stator which contains the center of the orbit of the pistons, partitions situated

diameter of the stator which contains the center of the orbit of the pistons, partitions situated approximately diametrically opposite each other and carried by a disk and in 5 one element of the pump-motor combination means for angularly displacing said disk and the partitions carried thereby.

In testimony whereof I have signed my name to this specification in the presence of two subscribing witnesses.
